Inventor:

Richard Ernst

UNITED STATES PATENT OFFICE

RICHARD ERNST, OF REICHENBACH, NEAR WALDHEIM, GERMANY

BLOTTING DEVICE

Application filed March 18, 1931. Serial No. 523,527, and in Germany January 26, 1931.

The object of the present invention is to produce a blotting device whereby a large portion of wet writing can easily be covered and whereby a uniform utilization of the blotting paper can be achieved, and the invention consists in the provision of a roller covered with the blotting paper and of a forked handle wherein said roller is rotatably mounted.

10 The paper may be attached either to an integral roller or to a roller divided into hingedly connected parts adapted to clamp the ends of the paper strip between them.

15 Fig. 1 of the accompanying drawing represents a sectional top view of one form of the blotting device,

Fig. 2 is a view of a blotting roller divided into two halves,

20 Fig. 3 is another end view showing the parts opened out, and

Fig. 4 is a view of part of the handle.

The blotting device comprises a roller which is covered with felt *b* as a resilient support for a strip of blotting paper *c*.

25 In the arrangement shown in Fig. 1 the roller is integral and formed with an axial bore *d* for the reception of the inturned ends *e* of a wire fork *f*, the latter serving as a handle whereby the roller can be passed quickly over long stretches of writing. The paper *c* may be cut from a strip in lengths corresponding to the circumference of the roller. The two ends can be joined on the roller by means of a gummed paper strip arranged between the paper strip and the felt support *b*.

30 As an alternative, the roller may be provided with a recess to receive the ends of the blotting paper strip and with a clamping device for holding the paper in position.

35 The fork *f* is adapted to maintain itself in a spread-out position, as shown in Fig. 4, allowing it to be easily attached to and removed from the roller. A hand-grip *g* is provided with a bore into which the shank part of the fork is inserted and wherein the fork members are pressed together for the proper engagement of the fork with the roller.

40 The roller may be divided axially, as

shown in Figs. 2 and 3, into two halves *i* and *k* which are connected at one side by a hinge or hinges *m*. This arrangement allows the ends of the blotting paper strip to be tucked in between the two halves, as shown in Fig. 2, and clamped in position. The clamping effect is preferably obtained by means of a coil spring *o* one end of which is pivoted to a screw *n* on one part, the other end being hooked for connection to a similar screw on the other part. For the connection of the roller to the handle, one half of the roller is provided at the ends with sleeves *p* adapted to receive the ends *e* of the wire fork. The sleeves may be connected to the roller by means of screws and fastening plates as shown in Fig. 2.

45 The roller may be made of any suitable material and may be made hollow for lightness. The metal parts may be plated, and the entire device may be ornamented as desired.

50 The construction of the clamping device and of the handle may be modified without departing from the principle of the invention.

I claim:

55 The combination with a blotting roller divided into two hingedly connected halves, of a wire fork whose members are formed with pivot pins for the roller and tend to maintain themselves in a spread-out position, a hand grip adapted to be slipped on to said fork for clamping the members together, studs connected to the end faces of one half of said roller, and tension springs pivoted to the end faces of the other half of the roller and adapted to be hooked on to said studs.

RICHARD ERNST.
